UNITED STATES PATENT OFFICE.

JOHN B. WEIGAND, OF ATHENS, WISCONSIN, ASSIGNOR OF ONE-FOURTH TO
FERDINAND A. STRUPP, OF SAME PLACE.

VOTING-MACHINE.

SPECIFICATION forming part of Letters Patent No. 630,148, dated August 1, 1899.

Application filed September 30, 1898. Serial No. 692,297. (No model.)

To all whom it may concern:

Be it known that I, JOHN B. WEIGAND, a citizen of the United States of America, residing at Athens, in the county of Marathon and State 5 of Wisconsin, have invented certain new and useful Improvements in Voting-Machines; and I do hereby declare the following to be a full, clear, and exact description of the invention, such as will enable others skilled in the 10 art to which it appertains to make and use the same.

This invention is an improvement in voting-machines, the object of said invention being to provide a machine of this character 15 which shall be simple and compact in construction and will accurately register each vote, recording the number of votes cast for each and every candidate, so that the totals can be quickly and conveniently ascertained.

20 The invention contemplates a construction and arrangement of parts by which a separate registering mechanism is provided for each candidate for any and all offices to be voted for and includes certain locking devices by 25 which the several registering mechanisms relating to any particular office are securely locked upon the operation of any one in registering a single vote for that office, the said locking devices being released by depressing 30 a lever at one side of the machine or cabinet, while the total votes or tallies which appear through sight-openings in the front of the cabinet are normally covered by slides locked in place.

35 The invention further provides for voting what is termed a "straight ticket" by the operation of a single push-rod, which actuates the registering mechanism for every candidate included in such ticket and also actuates 40 locking devices coacting with the separate locking devices to prevent a repeating of the vote either for the straight ticket or for an individual candidate.

The invention furthermore provides for 45 making a record of any particular vote upon a tally-sheet for the purpose of challenging said vote, the mechanism by which this is accomplished being independent of and remote from the registering mechanisms, so as not to 50 interfere in any manner with the proper operation of the latter.

The particular construction of my improved voting-machine attains the above objects by positive operations of the several mechanisms and auxiliary devices, not only insuring an 55 accurate count or register of each individual and combination votes, but also surely prevents a voter registering more than a single vote for any one candidate or tampering with the machine in any way. 60

The following specification enters into a detail description of my invention, reference being had to the accompanying drawings, and to letters thereon, which designate the different parts or instrumentalities, and what I consider to be novel in particular features and combinations is more specifically set forth in the appended claims. 65

Referring to the annexed drawings, which form a part of the specification, Figure 1 is 70 a front perspective view of a voting-machine constructed in accordance with my invention. Fig. 2 is a side elevation, partly in section, with the hinged back swung open to deposit the tally-sheet into the lower compartment 75 of the cabinet. Fig. 3 is an enlarged detail view of one of the drawers of the cabinet, showing two sets of registering mechanisms, including the devices for locking the push-rods. Fig. 4 is a sectional view on the line 44 80 of Fig. 3. Fig. 5 is a sectional view on the line 55 of Fig. 3. Fig. 6 is a sectional view on the line 66 of Fig. 3. Fig. 7 is a sectional view on the line 77 of Fig. 3. Fig. 8 is a detail view illustrating one of the slides which 85 cover the sight-openings in the front of the cabinet. Fig. 9 is a detail view of one of the side pieces of the cabinet and illustrating the slide which releases the locking devices. Fig. 10 is an enlarged detail view of one of the rock-shafts in section, showing the shape of said 90 shaft at the point where the flat spring engages.

In carrying out my invention I construct a cabinet the lower part of which forms a 95 closed compartment A, above which the side pieces a^1 extend and are connected at their upper ends by a top board a' . Adjoining one of the side pieces of the cabinet is a vertical partition a^2 , and between this partition and 100 the opposite side piece a^1 is a vertical series of horizontal partition-boards a^3 , forming

drawer-compartments extending the entire width between said partition and side piece. The backboard A' of the cabinet proper is hinged to the upper part of the closed compartment A for the purpose hereinafter explained.

Within the drawer-compartments are located drawers B, which are divided by partitions b into a number of small compartments, 10 each compartment containing a set of registering mechanisms and locking devices, separated by a transverse partition b', and as said registering mechanisms and locking devices are identically the same in the compartments 15 of each and every drawer a description of those in one compartment will apply to all. Therefore, referring more particularly to Fig. 3 of the drawings, C designates a transverse shaft which is journaled at its ends in blocks 20 c, and upon this shaft is keyed a ratchet-wheel C' and gear-wheel C², the latter meshing with a corresponding gear-wheel d, loosely mounted on a transverse shaft D and fast to a digit-wheel or drum D', having a peripheral 25 series of numerals running from "0" to "9" and representing units of the register. Also made fast to the shaft C is a disk C³, having a single projecting tooth c³, which is adapted to turn a toothed wheel d', loosely mounted on 30 the shaft D and fast to a digit-wheel D², representing tens, said digit-wheel carrying a gear-wheel d², meshing with a gear-wheel C⁴, connected to a disk C⁵, having a tooth c⁵, adapted to turn a toothed wheel d³, attached to a digit-wheel D³, representing hundreds. The digit-wheel D³ carries a gear-wheel d⁴, in mesh with a gear-wheel C⁶, loose on the shaft C and fast 35 to a disk C⁷, with a tooth c⁷ to turn a toothed wheel d⁵, carrying a digit-wheel D⁴, representing thousands. It will be understood that the toothed wheels carrying the digit-wheels each have ten teeth, and by gearing said digit-wheels to the disks having a tooth adapted to engage the toothed wheels of the next digit-wheels the digit-wheels are turned progressively 40 by the turning of the first gear-wheel C², which may be and is operated by the ratchet-wheel C', both being fast to the shaft C and the only wheels that are fast to said 45 shaft. In order to prevent accidental movement of the digit-wheels, the toothed wheels thereof are engaged frictionally by a spring-pawl or dog d⁸, Fig. 4. The numerals on the digit-wheels appear through sight-openings b⁸ in the front of the drawers, and in setting 50 said mechanism the zero-mark of each digit-wheel is brought on a line with said sight-openings. These sight-openings are normally covered by slides E, fitting in dovetailed recesses in the inner side of the front of the 55 drawers and locked in place at one side of the cabinet.

The registering mechanisms hereinbefore described are operated by independent push-rods F, which are passed through the front of the drawers and through the transverse partitions b', being provided at their outer ends

with a button F', said push-rods overlying the ratchet-wheels C'. Above the ratchet-wheels the push-rods are slotted to receive a gravity-pawl f, which engages said ratchet-wheels and turns them the extent of one tooth upon each operation of said push-rods. The push-rods are projected to their normal position by means of a helical spring f', bearing against 70 the partition b' and a bend in the rod, Fig. 5, while backward rotation of the ratchet-wheel C' is prevented by a spring-pawl f². The rear end of the push-rod extends into the rear compartment of the drawer and is 80 engaged by a locking device that engages a notch f³ in said rod.

It will be here noted that the registering mechanisms of each drawer all record votes for a particular office and are operated independently, the offices being designated in a vertical column at one side of the cabinet, (see Fig. 1,) while the names of the candidates for the offices are arranged on a horizontal line therewith, the push-buttons being 85 conveniently located at one side of the names. The candidates are also disposed so as to be in vertical columns below headings indicating the political parties to which the candidates belong. Now in order to lock all the 90 registering mechanisms referring to a particular office upon the operation of any one thereof a tumbling-rod G extends across the rear part of each drawer through the partitions b and is provided with upwardly-projecting pins g, engaged by outwardly-projecting pins f⁴ on the push-rods, the said tumbling-rod having rearwardly-projecting fingers g' engaging angle-slots h in pivoted plates H and adapted to turn said plates into 95 engagement with the notches f³ in the push-rods. The plates H are held in locked engagement with the push-rods by plate-springs I, attached to the rear wall of the drawers and bearing upon the tumbling-rods, the latter being flattened, as shown in Fig. 10, to increase the frictional engagement. Though all the locking-plates of any one drawer are brought into 100 engagement with their push-rods upon the operation of any one push-rod of that drawer, the said operated push-rod is not engaged until it returns to its normal position, the locking-plate bearing against the side of the rod until it is in position for said plate to enter 105 the notch, and to this end the fingers g' are 110 of spring metal to possess the required resiliency. The locking-plates are released by a slide J, positioned in a dovetailed recess in the side piece a⁸ of the cabinet, Fig. 3, and provided with projecting pins j, adapted to 115 engage pins g², projecting from the tumbling-rod G at right angles to the aforesaid pins, the slide J being operated by a lever J', pivoted to the cabinet and connected to said 120 slide by a pin j', working in a slot in the side 125 piece of the cabinet.

Having thus described the mechanisms and manner of registering votes for the several offices separately, I shall now proceed to de-

- scribe devices by which I provide for voting a straight ticket, through the intervention of which all the registering mechanisms for the candidates of any political party can be operated by pushing in a single push-rod. To this end rods K extend vertically through the cabinet proper, one for each vertical series of registering mechanisms, Figs. 2 and 6, and extending from said rods are plate springs or pawls *k*, which engage ratchet-wheels L on the transverse shafts C of the registering mechanisms, said ratchet-wheels being similar to the ratchet-wheels C' and are also keyed to the shaft, being engaged frictionally by spring-pawls *l*. The vertical rods *k* are operated by push-rods M, having button M', and for this purpose the said push-rod is provided with opposite cams *m m*, engaging the upper and lower walls of a slot in the rod K.
- 20 The operation of the push-rod acts to depress the rod K, and the pawls *k*, carried by said rod, turn the ratchet-wheels L and actuate the registering mechanisms in the same manner as the pawls C'. The push-rods for operating the rods K are located at the head of the political columns, as shown in Fig. 1, and when one is pushed in it operates all the registering mechanisms below, as hereinbefore stated.
- 30 In order to lock all of the registering mechanisms upon the operation of any one of the push-rods indicating a straight ticket, and thereby prevent a voter from registering a vote for any individual candidate after voting a straight ticket, the operation of any one of the vertical rods K is made to rock all the tumbling-shafts G and lock all of the push-rods. To the accomplishment of this, each drawer B is provided with a transverse tumbling-rod N, having a long arm *n*, engaged by a pin *h'*, projecting from the rod K, and a short arm *n'*, engaging a bent arm *g'*, extending from the tumbling-rod G, the said short arm working in a slot in the partition *b'*. It will be seen, therefore, that upon a depression of any one of the rods K the tumbling-rods G will all be rocked and actuate all of the locking devices.
- 40 To provide for making a record of any vote for the purpose of challenging said vote, the rear ends of the push-rods are provided with pins *o*, which extend through perforations in the rear walls of the drawers and are adapted to punch through a tally-sheet, (designated by the letter P,) which is placed against the rear ends of the drawers, being held in place by the hinged backboard A'. The backboard is provided with recesses on a line with the pins *o*, into which said pins pass after piercing the tally-sheet, and in order to move the tally-sheet away from the backboard when the latter is swung open a spring-projected wire frame R is hinged at its lower end to the inner side of said board and is connected at its upper end to helical springs *r*. The tally-sheets are deposited into the lower compartment of the cabinet through a slit s. It will
- be understood, of course, that the tally-sheets are provided with spaces and names corresponding with those on the front of the cabinet, so that the perforation or perforations in said tally-sheet will denote for which candidates or combination of candidates the voter voted, the name of the voter being written on the tally-sheet before it is inserted in the machine.
- 50 From the foregoing description in connection with the accompanying drawings the construction and operation of my improved voting-machine will be readily understood, for supposing a voter wishes to register a straight Democratic vote the button M' at the head of the first political column to the left is pushed in, which will depress the corresponding rod K, and thereby actuate the registering mechanisms for all the candidates in that column, the said rod K also operating the locking devices, and when the push-rod is released its locking-plate will enter the notch in said rod and also lock it against movement. After the voter has left the booth the ballot-clerk depresses the lever J', which releases the locking devices, and the machine is then set or ready for another voter. Should the next voter desire to register a split ticket, the operation of each push-rod independently will lock only the registering mechanisms in the horizontal series or drawer in which said push-rod is located, and it will be noted that after one of the push-rods for an individual candidate is operated the push-rods for straight tickets become inoperative; also, that should an attempt be made to cheat the machine by simultaneously pushing in a button for a straight ticket and one for an individual candidate it would result in the said candidate receiving but one vote, the operating-shaft of the registering mechanism for that candidate being then operated the extent of only one tooth by both the ratchet-wheels C' and L. After the closing of a ballot the slides E are unlocked and withdrawn, when the total number of votes cast for each and every candidate will appear through the sight-openings in the front of the cabinet, and as the act of voting a straight ticket registers one vote for each individual candidate on said ticket there is no figuring required.
- 60 The machine is compact and the entire mechanism is adjusted and arranged to work smoothly and easily in order that an accurate account of each and every vote may be correctly registered. It will also be observed that the parts are not liable to get out of order and that a positive movement is imparted upon each operation of a push-rod.
- 70 To reset the registering mechanisms, the drawers are withdrawn, and after releasing the pawls which engage the ratchet-wheels C' and L the digit-wheels can be turned by hand until they are in proper position, with the zero-marks appearing through the sight-openings. Though the registering mechanisms are shown as registering only to nine thousand nine hun-

dred and ninety-nine, it is apparent that the capacity could be increased by adding more wheels.

Having thus fully described my invention, 5 what I claim as new, and desire to secure by Letters Patent, is—

1. In a voting-machine, the combination with the registering mechanisms and rods operating the same, of locking devices for the rods comprising pivoted plates adapted to engage said rods, a tumbling-shaft actuated by the rods, and means operating the pivoted plates from the tumbling-shaft, substantially as shown and for the purpose set forth. 10
2. In a voting-machine, the combination with the registering mechanisms and rods operating the same, of locking devices for the rods comprising pivoted plates adapted to engage said rods and provided with angle-slots, 15 a tumbling-shaft actuated by the rods, and spring-fingers projecting from the tumbling-shaft into the angle-slots of the pivoted plates, substantially as shown and for the purpose set forth. 20
3. In a voting-machine, the combination with the registering mechanisms and rods operating the same, of locking devices for the rods comprising pivoted plates adapted to engage said rods, a tumbling-shaft actuated by 25 the rods, means operating the pivoted plates from the tumbling-shaft, and plate-springs bearing upon said tumbling-shaft, the latter being flattened where the plate-springs engage, substantially as shown and for the purpose set forth. 30
4. In a voting-machine, the combination with the registering mechanisms and rods operating the same, the latter having outwardly-projecting pins and notches near their rear ends, of locking devices for the rods comprising pivoted plates adapted to engage the notches in said rods, a tumbling-shaft having pins engaged by the pins of the operating rods, and spring-fingers projecting from the 40 tumbling-shaft into angle-slots in the pivoted plates; together with plate-springs bearing upon the tumbling-shaft, the latter being flattened where the plate-springs engage, substantially as shown and for the purpose set forth. 45
5. In a voting-machine, the combination with the registering mechanisms and rods operating the same, of locking devices for the rods comprising pivoted plates adapted to engage said rods, a tumbling-shaft connected to the plates and operated by the rods, said tumbling-shaft having an outwardly-projecting pin at one end, a slide having a pin engaging the pin of the tumbling-shaft, and 50 means for operating said slide, substantially as shown and for the purpose set forth. 60

6. In a voting-machine, the combination with the registering mechanisms and rods operating the same, said registering mechanisms being arranged in horizontal series; of locking devices for the operating-rods comprising pivoted plates adapted to engage said

rods and provided with angle-slots, tumbling-shafts actuated by the operating-rods, spring-fingers projecting from the tumbling-shafts, 70 into the angle-slots of the pivoted plates, and pins projecting from one end of the tumbling-shafts; together with a slide having projecting pins adapted to engage the pins of the tumbling-shafts, and means for operating said 75 slide, substantially as shown and for the purpose set forth.

7. In a voting-machine, the combination with the registering mechanisms comprising in part an operating-shaft having a ratchet-wheel keyed thereon, independent operating-rods for said mechanisms, vertical rods having pawls engaging the ratchet-wheels of the registering mechanisms in vertical series, and means for operating said vertical rods; together with pivoted plates adapted to engage the operating-rods, and devices preventing the operation of said plates upon the operation of any one of the vertical rods, substantially as shown and for the purpose set forth. 85

8. In a voting-machine, the combination with the registering mechanisms arranged in vertical and horizontal series, of independent operating-rods for the registering mechanisms, rods operating the registering mechanisms of each vertical series, pivoted plates adapted to engage the independent operating-rods, tumbling-shafts extending across the machine adjacent each horizontal series of independent operating-rods, means connecting the tumbling-shafts to the pivoted plates; said tumbling-shafts being operated either independently by the independent operating-rods or collectively by the vertical rods, substantially as shown and for the purpose set forth. 95

9. In a voting-machine, the combination with the registering mechanisms arranged in vertical and horizontal series, of independent operating-rods for the registering mechanisms, rods operating the registering mechanisms of each vertical series, pivoted plates adapted to engage the independent operating-rods and provided with angle-slots, tumbling-shafts extending across the machine adjacent each horizontal series of independent operating-rods, spring-fingers projecting from the tumbling-shafts into the angle-slots of the pivoted plates; said tumbling-shafts being operated either independently by the independent operating-rods or collectively by the vertical rods; together with a slide engaging the tumbling-shafts to bring them to their normal position, and means for operating said slide, substantially as shown and for the purpose set forth. 115

10. In a voting-machine, the combination with the registering mechanisms arranged in vertical and horizontal series, of independent operating-rods for the registering mechanisms, rods operating the registering mechanisms of each vertical series, operating-rods for said vertical rods, pivoted plates adapted to engage the operating-rods and provided with angle-slots, tumbling-shafts extending across 120

125

130

the machine adjacent each horizontal series of operating-rods, spring-fingers projecting from the tumbling-shafts into the angle-slots of the pivoted plates; said tumbling-shafts being operated either independently by the independent operating-rods or collectively by the vertical rods; together with means for bringing the tumbling-shafts to their normal position, substantially as shown and for the purpose set forth.

11. In a voting-machine, the combination with the registering mechanisms arranged in vertical and horizontal series, of independent operating-rods for the registering mechanisms, rods operating the registering mechanisms of each vertical series, operating-rods for said vertical rods having cams engaging the same, pivoted plates adapted to engage the operating-rods and provided with angle-slots, tumbling-shafts extending across the machine adjacent each horizontal series of operating-rods, spring-fingers projecting from the tumbling-shafts into the angle-slots of the pivoted plates, rock-shafts extending parallel with the tumbling-shafts, and arms projecting from the rock-shafts to operate the tumbling-shafts and be operated by the vertical rods; said tumbling-shafts being operated either independently by the independent operating-rods or collectively by the vertical rods; together with means for bringing the tumbling-shafts to their normal position, substantially as shown and for the purpose set forth.

12. In a voting-machine, the combination of a cabinet comprising a series of drawers divided into compartments, independent registering mechanisms located in said compartments, the front of the drawers being provided with sight-openings, removable slides extending across the front of the drawers to cover said sight-openings, and independent operating-rods for the registering mechanisms; together with pivoted plates adapted to engage said rods, tumbling-shafts extending across the rear ends of the drawers, and spring-

fingers connecting the tumbling-shafts to the pivoted plates, the tumbling-shafts being turned by the operating-rods, substantially as shown and described.

13. In a voting-machine, the combination with the registering mechanisms and operating-rods therefor, of horizontal pins or points projecting from the rear ends of the operating-rods through the back of the cabinet or machine, a vertical hinged board having recesses on a line with said pins, a skeleton frame pivoted to the lower end of the vertical board, and springs projecting the upper or free end of said skeleton frame; together with a tally-sheet placed upon the skeleton frame, and a closed receptacle at the lower end of the cabinet, said receptacle having a slit in its upper end through which the tally-sheet may pass, substantially as shown and for the purpose set forth.

14. In a voting-machine, the combination of a cabinet comprising a series of drawers, independent registering mechanisms located in said drawers, operating-rods for said mechanisms, pins or points projecting from the operating-rods through the rear ends of the drawers, a hinged board adapted to close against the rear ends of the drawers and provided with recesses on a line with the pins, a spring-projected frame connected to the inner side of said board, and a tally-sheet placed between the frame and rear ends of the drawers of the cabinet; together with a closed receptacle at the lower end of the cabinet, said receptacle having a slit in its upper end through which the tally-sheet may pass, substantially as shown and for the purpose set forth.

In testimony whereof I affix my signature in presence of two witnesses.

JOHN B. WEIGAND.
